UNITED STATES PATENT OFFICE.

NICOLL C. ODDO, OF MONTICELLO, NEW YORK.

DESIGN FOR A COAT-HANGER.

SPECIFICATION forming part of Design No. 35,346, dated November 26, 1901.

Application filed October 8, 1901. Serial No. 77,996. Term of patent 7 years.

To all whom it may concern:

Be it known that I, NICOLL C. ODDO, a citizen of the United States, residing at Monticello, in the county of Sullivan and State of New York, have invented and produced a new and useful Design for Coat-Hangers, of which the following is a specification.

My invention relates to a new and useful design for coat-hangers, of which the following is a specification, reference being had to the accompanying drawings, forming a part thereof, in which—

Figure 1 is a perspective of a device made in accordance with my new design. Fig. 2 is a rear elevation of the same.

Like numerals of reference designate like parts in the different views of the drawings.

The leading or material feature of my design consists of a semicircular rim or collar 1, beveled off on the ends at 2, and two shoulder members 3, sloping downwardly from the bot-

tom of the collar, convex transversely on the top and rounded off at front and rear on curves 4 and 5, respectively. The curves 4 are joined to the points of the collar, and the curves 5 are connected by a curve 6 of opposite curvature, thereby forming a double-reverse curve. A plane portion is connected to the inner side of the collar 1.

Having described my invention, what I claim as new, and desire to secure by Letters Patent, is—

The design for a coat-hanger, substantially as shown and described.

In testimony whereof I have hereunto set my hand in presence of two subscribing witnesses.

NICOLL C. ODDO.
